UNITED STATES PATENT OFFICE.

ALFRED LLOYD, OF LONDON, ENGLAND.

ELECTROTHERAPEUTIC APPLIANCE.

Application filed September 30, 1924. Serial No. 740,698.

To all whom it may concern:

Be it known that I, ALFRED LLOYD, a subject of the King of Great Britain, residing at 47 Brockenhurst Gardens, Mill Hill, London, in the county of Middlesex, England, have invented a certain new and useful Electrotherapeutic Appliance, of which the following is a specification.

This invention relates to a new or improved electro-therapeutic appliance primarily intended for the treatment of obesity, but which may be used for any other purposes to which same may be applicable.

Broadly, the electro-therapeutic apparatus according to this invention comprises electrically conductive rotative members having an axially undulating contour, and forming rolling electrodes for application to the exterior of the human body and means for supplying electric current to said electrodes.

The apparatus is advantageously formed as a complete and self contained unit i. e. the frame which supports the rolling members preferably carries a source of electric energy which may be a small dry battery (of say 1½ volts), a high frequency interrupter, an induction coil and a convenient "make and break" device actuated for example by one of the rolling members.

The electrical apparatus may of course be separate, and connected to the appliance in any convenient manner.

The rolling members are freely mounted with their axes in substantially parallel relation; and, in use, are rotated by frictional contact with the flesh of the person, the flesh (which is slightly compressed between the protuberances of the rollers) completing the electrical circuit across said rollers which latter are connected respectively to the two terminals of the secondary winding of the induction coil through the "make and break" device.

My present invention may be carried into practice as follows:—

Attached to a metal platform are two brackets in which are freely mounted a pair of metal rollers, each comprising an integral series of protuberances, preferably conoidal, with the axes of the cones in longitudinal alignment, the cones of one roller being reversed with respect to those of the other, i. e. with their apices facing in opposite directions, so that when said rollers

are being moved over the person, the flesh is gently compressed between the opposing conical surfaces.

A small dry battery, a high frequency interrupter, and an induction coil are mounted on the other side of the platform, one terminal of the induction coil secondary being connected through a make and break device to one of the said rollers, and the other terminal to the other roller.

A convenient make and break arrangement for use in the apparatus of this invention comprises a plunger, actuated by a cam on one of the roller spindles, and bearing continually against one end of a leaf spring mounted between a pair of metal contact arms the latter being secured to a common terminal connected to one pole of the induction coil secondary. During revolution of the rollers the leaf spring is lifted by the plunger into contact with one of the said arms, the reaction of the spring serving to keep the plunger in contact with the cam, and to depress the plunger when the cam moves past, until said spring touches the lower contact arm. Thus contact is made twice in each revolution of the roller.

Any suitable means may be provided to vary the resistance in circuit with the primary winding of the induction coil.

Such embodiment of the invention is illustrated in the accompanying drawings in which:—

Fig. 1 is a side view in elevation of the complete appliance.

Fig. 2 is a plan view from above with the electrical arrangement shown in broken lines.

Fig. 3 is a plan view of the underside of the appliance.

Fig. 4 is a cross-sectional view on line 4—4. Fig. 2.

Fig. 5 is a circuit diagram of the electrical connections.

Referring to these drawings:—

A designates a metal plate provided with members B in which a pair of rolling electrodes C and C¹ are mounted to rotate freely. Each of these rolling electrodes C and C¹ comprises a series of conoids, the parts of greater diameter in one roller being arranged substantially opposite the parts of smaller diameter in the other roller, so that the gap between the electrodes is substantially constant throughout their length.

The electrode C is electrically insulated from the members B, for example by mounting the spindle C^x in bearings of insulating material, or by providing an insulating sleeve 5 between said spindle and the body of the electrode. The electrode C¹ is in electrical contact with the members B.

On the upper side of the plate A is an electric battery D, a switch E, an induction 10 coil or transformer F, the core F¹ of which is provided with rack teeth meshing with a pinion operated by a hand wheel G, a high frequency interrupter H, a condenser J and a "make and break" device K.

15 The ratio of primary to secondary winding of the induction coil F is advantageously of the order of one to six or thereabouts.

The circuit connections are as follows (referring to Fig. 5) :—

20 The positive pole of the battery D is connected to one end of the primary winding F¹, the other end of which is connected to the windings H¹ of a horseshoe electromagnet, and these windings H¹ are connected to 25 a platinum or the like contact point H⁵. The armature H² of the electro magnet is carried on an electrically conductive spring arm H³ arranged over the contact H⁵, the end H⁴ of the spring arm H³ being connected 30 through the switch E to the negative pole of the battery D, a condenser J being shunted across the circuit.

35 L is an adjusting screw passing through the case of the appliance and bearing on the spring arm H³ for the purpose of adjustment.

40 One end of the secondary winding F² of the induction coil F is connected to a terminal K¹ carrying contact arms K² and K³ (see Fig. 4 also) with which alternately the arm K⁴ makes contact.

45 The current passes from the arm K⁴ through the plunger L insulated from the plate A (see Fig. 4) onto the cam M fixed to the roller C, from the latter through the flesh of the patient to the roller C¹ and thence through the members B and plate A to the other end of secondary winding F² connected to said plate A to complete the 50 circuit.

55 A terminal N connected to terminal K¹ is provided for connection to a plate or other electrode in cases where it is desired to pass a current from such electrode through the body of the patient to the rolling electrodes, in addition to the intermittent current flowing between said rolling electrodes twice in each revolution thereof.

60 The appliance is provided with handles O secured to the members B which are stayed by rod P.

65 Although I have described and illustrated herein, one form of appliance according to my invention, yet various modifications may be made without departing from the scope

of the invention. For example, although the conoidal form of the rolling electrodes has been found to give the best results in practice, the flesh of the patient appearing to be gently compressed or squeezed between the opposing conical surfaces whilst the intermittent current causes successive contractions of the compressed parts, yet any other suitable form of axially undulating rolling electrode may be employed. 70

75 Furthermore the frame of the appliance need not conduct current and therefore need not be of conductive material, the electrode C¹ in such a case being connected by a lead or in any convenient manner to the secondary winding of the induction coil. 80

What I claim is :—

1. An electro-therapeutic appliance comprising a frame, a plurality of elongate electrodes of axially undulating contour and of opposite polarity mounted to rotate in said frame by frictional contact with the flesh of the patient, means to supply electric current to said electrodes, and a make and break device in the circuit actuated 85 automatically by the rotation of the electrodes, the current flow being from one electrode to another through the flesh of the patient. 90

95 2. An electro-therapeutic appliance comprising a frame, a plurality of elongate rotative electrodes of axially undulating contour mounted in said frame, a source of electro-motive force connected through an interrupter to the primary winding of an induction coil, the secondary of which is connected to the rotative electrodes, and a make and break device automatically actuated by the rotation of the electrodes in the 100 said secondary circuit, the current flow being from one electrode to another through the flesh of the patient. 105

110 3. An electro-therapeutic appliance comprising a frame, a pair of elongate metallic electrodes mounted parallel therein to rotate by frictional contact with the flesh of the patient and each having a series of conoidal protuberances, a battery, a high frequency interrupter and an induction coil the primary winding of which is connected in series with said battery and said interrupter the secondary winding being connected through an automatically actuated make and break device to said rolling electrodes of opposite polarity. 115

120 4. An electro-therapeutic appliance comprising a frame, suitable handles for said frame, a pair of elongate metallic electrodes mounted parallel in said frame so as to rotate by frictional contact with the flesh of the patient, each of said electrodes having a series of conoidal protuberances arranged in staggered relation to the protuberances of the other electrode, a battery, connected through an interrupter to the primary wind- 125

ing of an induction coil the secondary winding of which is connected to said electrodes through a make and break device actuated by the rotation of one of said electrodes the circuit between the latter being completed through the flesh of the patient.

5. An electro-therapeutic appliance comprising a frame, suitable handles for said frame, a pair of elongate rotative electrodes each having a series of conoidal protuberances arranged in staggered relation to the protuberances of the other electrodes, a battery connected in circuit with an interrupter

and the primary winding of an induction coil having its secondary winding connected to said electrodes through a make and break device comprising a pair of spaced metallic arms carried by a common terminal in the secondary circuit and an intermediate contact arm actuated by a plunger rolling on a cam carried by one of the electrodes, the secondary circuit between the electrodes being completed through the flesh of the patient. ¹⁵ ²⁰

ALFRED LLOYD.
